(57) **CLAIM**

The ornamental design for a one touch and expandable power and data center, as shown and described.

DESCRIPTION

FIG. 1 is a perspective view of a one touch and expandable power and data center in accordance with my invention;
 FIG. 2 is a perspective view of a one touch and expandable power and data center in accordance with my new invention, shown in a closed position;
 FIG. 3 is a top plan view of the one touch and expandable power and data center in accordance with my invention;
 FIG. 4 is a left side view of the one touch and expandable power and data center in accordance with my invention;
 FIG. 5 is a front elevation view of the one touch and expandable power and data center in accordance with my invention;
 FIG. 6 is a right side elevation view of the one touch and expandable power and data center in accordance with my invention;
 FIG. 7 is a bottom plan view of the one touch and expandable power and data center in accordance with my invention; and,
 FIG. 8 is an upside down rear elevation view of the one touch and expandable power and data center in accordance with my invention.
